(57) **CLAIM**

The ornamental design for a fitness equipment as shown and
described.

DESCRIPTION

FIG. 1 is a front and right side perspective view of an
embodiment of a fitness equipment showing our new design.

FIG. 2 is a front and left side perspective view thereof.

FIG. 3 is a front view thereof.

FIG. 4 is a back view thereof.

FIG. 5 is a left view thereof.

FIG. 6 is a right view thereof.

FIG. 7 is a top view thereof; and,

FIG. 8 is a bottom view thereof.

The dash-dash-dash broken lines are included for the
purpose of illustrating portions that form no part of the claimed
design.

1 Claim, 8 Drawing Sheets
